UNITED STATES PATENT OFFICE.

WILLIAM HALKET, OF HOLYOKE, MASSACHUSETTS.

PEN AND PENCIL CLIP.

Application filed March 26, 1925. Serial No. 18,647.

This invention relates to improvements in pen and pencil clips and its leading object is to provide a clip of this character with a gripping bar having an integral button back 5 provided with spring locking flanges adapted to fit into the socket of a celluloid button, and having an offset spherical bearing projection.

With the above the other objects in view 10 the invention consists in certain new and useful constructions, combinations and arrangements of parts, clearly described in the following specification and fully illustrated in the accompanying drawings, in which:—

Fig. 1 is a rear elevation of the improved 15 clip, showing a button mounted thereon.

Fig. 2 is a rear elevation thereof showing the button removed.

Fig. 3 is an edge view of the button back.

Fig. 4 is a transverse sectional view on the line 4—4 of Fig. 1.

Referring to the accompanying drawings illustrating the practical construction of the invention 5 designates a spring gripping, 20 bar lever which is formed on one end with a holding band 6 for receiving a pen or pencil and on the other end with an integral button back 7 for receiving a button or emblem or the like.

The button back 7 is provided with a forwardly offset marginal edge flange 8 which is formed with a notch 9 at the point where it joins the gripping bar 5.

A spherical struck up bearing projection 14 is formed on the rear of the button back by drawing the metal of which the entire article is composed. This projection which is eccentrically central located serves to

space the rear face of the button back from the garment engaged by the clip. 40

The entire article, excepting of course, the button 12, is made from a single piece of sheet metal.

13 designates an annular struck up rib on the rear of the button back. It is to be understood that I do not limit myself to the exact location of the struck up projection 14 as it may, if desired, be eccentrically located with relation to the center of the button back. 50

Having described my invention I claim:—

1. An article holding clip consisting of a gripping bar having an article holding element on one end thereof and a button back which is integral with the gripping bar at 55 the other end for providing a bearing terminal on the other end thereof and means on the back of the button back to engage the article being gripped by the holding element.

2. An article holding clip consisting of a gripping bar having an article holding element on one end thereof and an integral button back on the other end thereof provided with a rearwardly offset spherical bearing projection. 65

3. An article holding clip consisting of a gripping bar having an article holding element on one end thereof and an integral circular button back formed on the other end thereof and provided with a forwardly offset spring marginal flange having a notch in its edge located in line with the gripping bar, and formed with a rearwardly projecting spherical bearing head. 70
